UNITED STATES PATENT OFFICE.

CHARLES J. HUNT, OF BARNSDALL, OKLAHOMA, ASSIGNOR OF ONE-HALF TO WILLIAM L. CLEM, OF BARNSDALL, OKLAHOMA.

DRYING TUMBLER.

Application filed October 20, 1925. Serial No. 63,740.

To all whom it may concern:

Be it known that I, CHARLES J. HUNT, a citizen of the United States, residing at Barnsdall, in the county of Osage and State of Oklahoma, have invented certain new and useful Improvements in Drying Tumblers, of which the following is a specification, reference being had to the accompanying drawings.

10 This invention relates to drying tumblers and it is an object of the invention to provide a device of this kind with means whereby air is effectively applied to the articles being dried in order to facilitate 15 the desired drying action together with means whereby such air may be effectively heated before entering the drying chamber.

Another object of the invention is to provide a machine of this kind wherein a blast 20 fan is employed for creating the requisite delivery of air to the drying chamber together with a blower fan coacting with the blast fan to assure an effective delivery of air to the drying chamber and which also 25 provides means to permit delivery to the drying chamber, when desired, of air of atmospheric temperature.

Furthermore, the invention has for an object the provision of means whereby the 30 liability of fire is substantially eliminated and which means also serves to maintain the articles being dried free from static and thus avoiding such articles collecting lint.

The invention consists in the details of 35 construction and in the combination and arrangement of the several parts of my improved drying tumbler whereby certain important advantages are attained and the device rendered simpler, less expensive and 40 otherwise more convenient and advantageous for use, as will be hereinafter more fully set forth.

The novel features of my invention will 45 hereinafter be definitely claimed.

45 In order that my invention may be the better understood, I will now proceed to describe the same with reference to the accompanying drawings, wherein:—

50 Figure 1 is a view in front elevation of a drying tumbler constructed in accordance with an embodiment of my invention;

Figure 2 is a view in side elevation of the device as herein disclosed;

Figure 3 is an enlarged vertical sectional view of the device as herein disclosed, the 55 heating unit being indicated in somewhat a diagrammatic manner.

As disclosed in the accompanying drawings, H denotes a housing the walls of which preferably constitutes galvanized iron suitably affixed to a supporting frame F of channel beams. The upper portion of the housing is provided with a loading door D of any desired construction and rotatably positioned within said housing H in close 60 proximity to said door D is a tumbling drum or cylinder T of any desired type, the supporting shaft 1 of which extends beyond a side wall 2 of the housing and having engaged therewith the pulleys 3 one of which 65 is tight and the other loose for coaction in a well known manner with a drive belt. I do not, however, desire to be understood as limiting myself to any particular driving means for the tumbling drum or cylinder T. 70

The lower portion of the housing H has arranged therein a supplemental floor S extending from the front wall 4 of the housing H to a predetermined point inwardly of the rear wall 5, the inner edge of the floor S 75 being continued by an upwardly disposed partition 6 terminating at a point slightly below a horizontal plane disposed through the axial center of the drum or cylinder T. Below the floor S and the main floor M of 80 the housing H is a horizontally disposed partition 7 the forward end of which is spaced from the front wall 4 of the housing and the inner end of said partition 7 terminates at a point substantially midway of the 85 partition 6 and the rear wall 5. The inner edge of the partition 7 is continued by an upwardly disposed partition 7'. The space between the rear wall 5 and the partition 7' provides a downwardly disposed air duct 8 90 leading from an air chamber 9, said chamber constituting a substantially cylindrical casing extending entirely along the upper 95 rear portion of the housing H.

Extending axially of the air chamber 9 100 is a shaft 10 rotatably supported by the side walls 2 of the housing H and extending outwardly beyond one of such walls, said extended portion of the shaft 10 being provided with the conventional pulleys 11 for 105 coaction with the drive belt. The shaft 10

within the air chamber is provided there-
along with the radial blades 12 which, upon
rotation of the shaft 10, force a blast of air
down through the air duct 8 through the
chamber 14 between the floor M and parti-
tion 7 and through the duct 15 between the
floor S and partition 7 and up through the
duct 16 between the partitions 6 and 7' and
discharging in a direction toward the drum
10 T, said direction of discharge being ob-
tained by the side portion of the wall of the
air chamber 9 overlying the upper end of
said duct 16 and the outward and upward
curve of the upper portion 6' of the parti-
tion 6. One end of the air chamber 9 opens
15 through a side wall 2 into a casing 17 car-
ried by the housing H and in which is
mounted a blower fan 18 in driven connec-
tion, as at 19, with the shaft 10, said blower
20 fan rotating at a relatively high speed and
serving to feed or deliver fresh air to the
air chamber 9 so that it will be assured that
an effective blast will be created by the
blades 12.

25 The chamber 14 constitutes a heating
chamber and, as herein disclosed, said cham-
ber has arranged therein the steam coils 20
whereby the air, when the steam is within
said coils, is raised to an extremely high
30 temperature so that the action of the air
blast upon the articles within the drum T
is materially increased. The coils 20 pref-
erably constitute a unit and the front wall
35 4 is provided with a door 21 whereby said
unit may readily removed or applied.

Should it be desired that the air delivered
to the drying chamber be cool, the steam is
40 shut off from the coils 20 and said coils
blown out whereupon the blower fan 18 will
45 maintain the requisite amount of cool air or
air at atmospheric temperature.

In communication with the lower forward
portion of the drying chamber through the
side walls 2 are the exhaust conduits 22.

50 Extending above the housing H at the for-
ward portion thereof is a steam line 23 pro-
vided with the depending branch lines 24
which extend within the housing H between
the heads 25 of the drum T and the side
55 walls 2 of the housing, the lower or inserted
ends of said branches being provided with
the jet nozzles 26 permitting a slight dis-
charge of steam within the housing, such
steam serving to kill off any static that may
60 occur during a working operation of the de-
vice to prevent fire and to also maintain
the articles being dried free from static so
that the same will not collect lint. Inter-
posed in the steam line 23 at any desired lo-
65 cation is a controlling or regulating valve
27.

From the foregoing description it is
thought to be obvious that a drying tumbler
constructed in accordance with my invention
65 is particularly well adapted for use by rea-

son of the convenience and facility with
which it may be assembled and operated,
and it will also be obvious that my invention
is susceptible of some change and modifica-
tion without departing from the principles 70
and spirit thereof and for this reason I do
not wish to be understood as limiting myself
to the precise arrangement and formation
of the several parts herein shown in carrying
out my invention in practice except as here- 75
inafter claimed.

I claim:—

1. A drying tumbler comprising, in com-
bination, a housing, a rotating tumbler drum
mounted within the upper portion of the 80
housing, an air chamber disposed across the
housing, an air duct leading therefrom and
disposed in a tortuous path and discharging
toward the drum, a blast fan arranged with-
in the air chamber, and an air feeding fan 85
delivering to the air chamber.

2. A drying tumbler comprising, in com-
bination, a housing, a rotating tumbler drum
mounted within the upper portion of the 90
housing, an air chamber disposed across the
housing, an air duct leading therefrom and
disposed in a tortuous path and discharging
toward the drum, a blast fan arranged
within the air chamber, and an air feeding 95
fan delivering to the air chamber and through
one end of said chamber.

3. A drying tumbler comprising, in com-
bination, a housing, a rotating tumbler drum
mounted within the upper portion of the 100
housing, an air chamber disposed across the
housing, an air duct leading therefrom and
disposed in a tortuous path and discharging
toward the drum, a blast fan arranged
within the air chamber, an air feeding fan 105
delivering to the air chamber, and a heating
unit interposed in the air duct.

4. A drying tumbler comprising, in com-
bination, a housing, a rotating tumbler drum
mounted within the upper portion of the 110
housing, an air chamber disposed across the
housing, an air duct leading therefrom and
disposed in a tortuous path and discharg-
ing toward the drum, a blast fan arranged
within the air chamber, an air feeding fan 115
delivering to the air chamber, and means
for discharging steam into the housing ad-
jacent to the drum.

5. A drying tumbler comprising, in com-
bination, a housing, a rotating tumbler drum
mounted within the upper portion of the 120
housing, an air chamber disposed across the
housing, an air duct leading therefrom and
disposed in a tortuous path and discharg-
ing toward the drum, a blast fan arranged
within the air chamber, an air feed- 125
ing fan delivering to the air chamber, and
means for discharging steam into the hous-
ing adjacent to the opposite ends of the
drum.

6. A drying tumbler comprising, in com-

bination, a housing, a rotating tumbler drum mounted within the upper portion of the housing, an air chamber disposed across the housing, an air duct leading therefrom and disposed in a tortuous path and discharging toward the drum, a blast fan arranged within the air chamber, an air feed-

ing fan delivering to the air chamber, said air feeding fan being in driven connection with the blast fan.

10

In testimony whereof I hereunto affix my signature.

CHARLES J. HUNT.
